UNITED STATES PATENT OFFICE.

JAMES VRBA, OF MARSHALLTOWN, IOWA, ASSIGNOR TO LENNOX FURNACE COMPANY,
OF MARSHALLTOWN, IOWA.

BASE RING FOR FURNACE CASINGS.

Application filed November 24, 1924. Serial No. 751,963.

To all whom it may concern:

Be it known that I, JAMES VRBA, a citizen of the United States, and a resident of Marshalltown, in the county of Marshall 5 and State of Iowa, have invented a certain new and useful Base Ring for Furnace Casings, of which the following is a specification.

In the construction of modern furnaces 10 there is usually provided a combustion chamber and a furnace casing surrounding it and spaced a considerable distance from it, and there is also usually provided a base ring for the furnace casing ordinarily made 15 of angle bar metal, to which the furnace casing is secured. These base rings of angle bar material are usually formed into a substantially complete circle and transported to the point where the furnace is to be installed. 20 They are quite bulky in size and in handling and transportation they are frequently distorted from their original shape, and it is a matter of considerable difficulty when installing a furnace to have these base 25 rings lay flat upon the surface upon which the furnace is being installed.

The objects of my invention are to provide a base ring of this character of simple, durable and inexpensive construction, made in 30 a number of cast metal sections, interchangeable with each other, and of a relatively short length so they may be easily transported and handled, and also so arranged that when fitted together they will interlock 35 with each other only when extended in a substantially complete circle, and which will lie substantially flat upon the surface on which the furnace is being installed.

My invention consists in the construction, 40 arrangement and combination of the various parts of my device, whereby the objects contemplated are attained, as hereinafter more fully set forth, pointed out in my claims, and illustrated in the accompanying drawings, in which:

Figure 1 shows a perspective view of a portion of a furnace having my improved base ring applied thereto and a portion of the furnace casing connected to the base 50 ring.

Figure 2 shows a top or plan view of two adjacent portions of my improved base ring members bolted together.

Figure 3 shows a side elevation of same.

Figure 4 shows a view similar to Figure 2 55 with the sections slightly spaced apart.

Figure 5 shows a sectional view on the line 5—5 of Figure 2.

Figure 6 shows a detail perspective view 60 of one end of one of the base ring sections.

Figure 7 shows a similar view of the opposite end; and

Figure 8 shows a vertical plan view of two adjacent base ring sections bolted together.

Referring to the accompanying drawings 65 I have used the reference numeral 10 to indicate that portion of a furnace shown and 11 the furnace casing. The furnace front which projects forwardly from the furnace combustion chamber is indicated generally 70 by the numeral 12.

My improved base ring as preferably constructed is made in five sections, all exactly alike, and so designed that they may be cast by an ordinary casting process. Each section comprises a flat base 13 and an upright rib 14. At one end there is an inwardly extended bolt receiving lug 15 having an opening 16 therein for a bolt. In the rib 14 adjacent to the lug 15 there is formed a bolt 75 opening 17. The surface adjacent to this bolt opening 17 on both sides of the rib 14 is depressed at 18 as shown in Figure 3. Formed on the under surface of the same end is a segmental depression 19, shown in 80 Figure 7, and the lower portion of the flange 14 projects over this depression 19 to form the flat face 20, as shown in Figure 7. The outwardly extended part of the base 13 adjacent to this shoulder 20 is beveled or inclined at 21, as shown in Figure 7.

The opposite end of the base ring member is formed with an inwardly extended rounded lug 22 having bolt openings 23, and this lug stands spaced above the bottom of the base 13, as shown in Figure 6. At the intersection of the lug 22 and the bottom of the base 13 there is a beveled or inclined shoulder 24, and the end of the base 13 projects beyond the upright flange 14 at 95 25

In practical use, and when connecting two of the adjacent members together, they are placed in position resting upon the surface on which the furnace is being erected. Then they are moved toward each other until the 100 shoulder 20 on one end engages and over-

laps the extending base member 25 on the other member. When this is done, the two bolt receiving lugs 15 and 22 will stand in overlapping positions ready to receive a bolt 26. Furthermore, when in this position the beveled shoulders 21 and 25 will engage, and a portion of the lug 15 will engage the beveled shoulder 24. When these parts are thus placed together the two base ring sections are then positioned and held against movement in every direction relative to each other, except straight apart, and they are held against such movement by the bolt. When the bolts are inserted as described, then all movement of every kind of these two parts relative to each other is prevented, and the bolts cannot be inserted until the parts are so alined as to form with each other a segment of a true circle. The two base ring members that are adjacent to the furnace front 12 may be permanently secured to the furnace front by bolts or rivets through the openings 17, and if desired the furnace casing may be secured to the base ring by bolts or rivets through the opening 17.

By having the depressions 18 surround the bolt holes 17, it is obvious that when bolts are inserted through the relatively soft sheet metal furnace casing, and the nuts thereon tightened, portions of the furnace casing will be forced into these depressions, thus aiding materially in holding the furnace casing firmly in position by the bolts, and also aiding in preventing the furnace casing from becoming torn or distorted by strains applied thereto, such as would be done but for the portions of the furnace casing drawn into said depressions.

Attention is directed to the fact that these furnace sections are all interchangeable, and in the event any one should become broken or defective, it would only be necessary to provide a new section, which can be very readily, quickly and easily placed in position.

The advantages of my improved sectional base ring for shipping and transportation are obvious, because the sections are of short length, and being of cast metal are not likely to be bent or distorted, such as is the case with a complete circle base ring made of angle bar. Furthermore, after the installation is complete, the furnace casing forms a relatively true circle, and the furnace casing stands properly spaced apart from the combustion chamber throughout its entire surface.

I claim as my invention:

1. A base ring for furnace casings, formed of a series of cast metal sections, each section having at each end an inwardly projected bolt receiving lug, one in a plane above the other, and each end also having coacting lugs designed to interlock with each other to prevent up and down and lateral movement of the sections relative to each other. 60

2. A base ring for furnace casings, comprising a number of independent cast metal sections, each section comprising a base portion and an upright casing engaging flange, and each section also having at each end inwardly projected bolt receiving lugs, one arranged in a plane above the other, and each section also having at each end coacting 70 projections and depressions so arranged that when two ends are fitted together, said projections and depressions and lugs will hold them in true alinement with each other and against either up and down or lateral movement, and whereby the sections are made interchangeable. 75

3. An improved base ring for furnace casings, comprising in combination a series of cast metal sections, each section comprising a base and an upright casing engaging flange, one end of each section being formed with an inwardly extended bolt receiving lug with its under surface flush with the bottom of the base, said end being also 80 formed with a recess on its under surface below the casing engaging flange, and also with a beveled outwardly extended end on the base portion, the other end being formed with an inwardly extended bolt receiving lug in a plane higher than that of the first mentioned bolt receiving lug, and also with a beveled portion at the end of the base adjacent to said bolt receiving lug, the base portion being extended beyond the upright 90 casing receiving flange, and said base portion being provided at its end with a beveled portion extended substantially straight outwardly, arranged and combined in substantially the manner set forth and for the purposes stated. 95

4. An improved base ring for furnace casings, comprising a series of cast segmental sections shaped at their ends to interlock with each other, and each provided with a base and an upwardly extended flange, there being at each end of the flange a bolt opening and a depression surrounding the bolt opening, for the purposes stated. 100

Des Moines, Iowa, November 6, 1924.
JAMES VRBA.
